UNITED STATES PATENT OFFICE.

TERRY STAFFORD, OF TOPEKA, KANSAS.

TRANSMISSION-GEARING.

No. 830,460.

Specification of Letters Patent.

Patented Sept. 4, 1906.

Application filed April 4, 1906. Serial No. 309,871.

To all whom it may concern:

Be it known that I, TERRY STAFFORD, a citizen of the United States, residing at Topeka, in the county of Shawnee and State of Kansas, have invented new and useful Improvements in Transmission-Gearing, of which the following is a specification.

My invention pertains to transmission-gears, such as employed in motor-vehicles, and more particularly to means for controlling the same; and it has for one of its objects to provide means whereby with one motion of an actuating device—such, for instance, as a lever—the clutch of a transmission-gear may be opened, the gears shifted into mesh wherever desired, and the clutch closed to connect the motor to the driving wheel or wheels.

Another object of the invention is the provision of auxiliary means for performing the single operation of opening or releasing the clutch when it is desirable so to do.

With the foregoing in mind the invention will be fully understood from the following description and claims, when the same are read in connection with the accompanying drawings, forming part of this specification, in which—

Figure 1 is a view illustrating in side elevation a transmission-gear case and my improvements properly arranged relative thereto. Fig. 2 is a plan view, partly broken away, showing so much of the transmission-gear as is necessary to illustrate the application of my improvements. Fig. 3 is an end elevation, or rather a projected view, of Fig. 1. Fig. 4 is a detail side elevation of the slide for moving the shifting gear to whichever speed is wanted. Fig. 5 is a top plan view of the same. Fig. 6 is a detail side elevation of the slide for opening or releasing the clutch and for moving the slide shown in Figs. 4 and 5 endwise, and Fig. 7 is a top plan view of the slide shown in Fig. 6. Fig. 8 is a detail side elevation illustrating swinging segments which may be employed in lieu of the slides N and L when desired.

Similar letters designate corresponding parts in all of the views of the drawings, referring to which—

A is a transmission-gear case. B is a shaft arranged in the said case; C, a multiple-disk clutch also arranged in the case; D, a heavy coiled spring for normally closing the multiple-disk clutch; E, a yoke through the medium of which the multiple-disk clutch is

opened or released against the action of the spring, and F a shifting gear movable on the shaft B in the direction of the length thereof and designed, in connection with other gears which I have deemed it unnecessary to illustrate, to regulate the speed at which the driving wheel or wheels (not shown) are rotated. These parts may be of the ordinary well-known construction or of any other construction compatible with the purpose of my invention without involving a departure from the scope thereof.

The yoke E is fixed on a transverse rock-shaft G, which is journaled in a suitable bearing H, carried by the case A, and to the said rock-shaft G, at the outer end thereof, is fixed a vertically-swinging lever I, which is arranged longitudinally of the case A and is provided adjacent to its free end with lateral inwardly-extending projections J and K, the said projections being preferably in the form of antifriction-rollers, as illustrated, and the projection K being arranged about the proportional distance illustrated above the projection J for a purpose which will be presently set forth.

L is an endwise-movable slide guided in the case A and having a slot a and also having recesses b in its upper edge and outer side, as best shown in Figs. 4 and 5. This slide carries an arm M, Figs. 2 and 3, which terminates at its inner end in a fork c, arranged to straddle the shifting gear F or rather span the circumferential groove d therein, and hence it will be apparent that when the slide is moved endwise the shifting gear F will be moved with it to regulate the speed at which the driving-wheel of the motor-vehicle is driven.

N is a slide guided in the case A and arranged at the outer side of the slide L and parallel therewith. The said slide N is connected with the slide L through the medium of a bolt e, disposed and movable in the slot a, and it is provided in its upper edge with notches f f and g g, the walls of which are inclined, as shown, and is also provided intermediate the said notches with neutral points h. It is further provided, and preferably at a point adjacent to the bolt e, with an outwardly-extending projection k, which is preferably in the form of a ball and is designed, in connection with a complementary socket l, Fig. 2, to join the slide to a rod m, which in turn is designed to be connected with a lever or other actuating device. (Not illustrated.)

I prefer that the said lever be of the ordinary type and that the sector employed in connection therewith be notched, so that the lever may be stopped at either of the neutral points 5 *h* on the slide *N*.

It will be apparent from the foregoing that when the slide *N* is moved endwise one of its notches will act against the projection *J* of lever *I* and in that way raise the lever and 10 turn the rock-shaft *G*, so as to swing the yoke *E* toward the left and through the medium of the same open the multiple-disk clutch *C* against the action of the spring *D*. It will also be apparent that the bolt *e* on slide *N* 15 will engage the end of the slot *a* in slide *L*, with the result that subsequent to the opening of the clutch *C* the slide *L* will be moved endwise by the slide *N* and with it the shifting gear *F*, this to slide the gear having the 20 rectangular aperture upon the squared shaft of the transmission-gear. From this it follows that with but one motion of the actuating device connected with the slide *N* the clutch of the transmission-gear is opened, the 25 shifting gear is placed in the position desired, and the clutch is closed to connect the motor to the driving wheel or wheels, closing of the clutch being permitted by one of the recesses *b* in slide *L* registering with the projection *J* 30 of the lever *I* and permitting downward movement of the projection and lever.

It will be gathered from the foregoing that the multiple-disk clutch being slow to take hold will allow shifting of the gear *F* in either 35 direction with impunity, and it will also be apparent that the gears are necessarily in absolute mesh before the clutch can be closed, which precludes stripping of the gears by applying power when the gears are only partly 40 intermeshed. This will be better appreciated when it is remembered that the slide *L*, carrying the gear-shifting arm *M*, has to be exactly positioned before projection *J* on lever *I* can drop into a recess *b*. In order that the 45 single operation of opening or releasing the clutch may be accomplished when necessity demands, I provide the cam-lever *P*. (Best shown in Fig. 1.) The said cam-lever is fulcrumed on case *A* and arranged under the 50 projection *K* on lever *I*, and hence it will be apparent that when it is thrown in the direction indicated by arrow in Fig. 1 it will act against projection *K* and raise lever *I*, and thereby open the clutch *C* against the action 55 of spring *D*. The lever *P* may be connected through a rod *Q* with an emergency-brake pedal (not shown) in order to enable the operator by the movement of the pedal to first open the clutch and then apply the brake, or 60 else the lever *P* may be connected with any other pedal to afford the option of opening the clutch through the lever or through the pedal. It will further be gathered from the foregoing that my improvements are simple 65 and well adapted to withstand the usage to

which motor-vehicle mechanism is ordinarily subjected and that the case *A* is dust and oil tight, and its lid *m* permits of access being readily gained to the interior parts.

I have entered into a detailed description of 70 the construction and relative arrangement of the parts comprised in the present and preferred embodiment of my invention in order to impart a definite understanding of the said embodiment. I do not desire, however, to be 75 understood as confining myself to the said specific construction and relative arrangement of parts, as such changes or modifications may be made in practice as fairly fall 80 within the scope of my invention as claimed.

In Fig. 8 of the drawings I have illustrated swinging segments *N'* and *L'*, which are designed when desired to be used in lieu of the slides *N* and *L*, respectively. These swinging segments *N'* and *L'* are notched and 85 grooved like the slides and are designed to coöperate with the lever *I* in the same manner as the said slides. In this connection I desire it understood that any means compatible with my invention may be employed for opening 90 the clutch and moving the shifting gear on one movement of an actuating device without involving a departure from the scope of the said invention as claimed. I also desire it understood that while I prefer to employ a 95 clutch of the multiple-disk type a cone or other form of clutch may be used without affecting my invention.

Having described my invention, what I claim, and desire to secure by Letters Pat- 100 ent, is—

1. The combination with the clutch and the shifting gear of a transmission-gear; of means for normally closing the clutch, a lever for opening the clutch, means for moving the 105 said lever in one direction, and means for serving the twofold purpose of shifting the gear and controlling movement of the lever in the other direction.

2. The combination with the clutch and the shifting gear of a transmission-gear, and means for normally closing the clutch; of a lever for opening the clutch; said lever being provided with a projection, means for moving the said lever in one direction, and a slide 115 connected with and arranged to move the shifting gear and having one or more recesses arranged to register with the projection of the lever to permit movement of the lever in the direction opposite to that stated.

3. The combination with the clutch and the shifting gear of a transmission-gear; of a lever for opening the clutch, means for moving the said lever in one direction, and means for serving the twofold purpose of shifting 125 the gear and controlling movement of the lever in the other direction.

4. The combination with the clutch and the shifting gear of a transmission-gear; of means for opening the clutch, and means for 130

serving the twofold purpose of shifting the gear and holding the clutch open until after the gear is fully shifted.

5. The combination with the clutch and the shifting gear of a transmission-gear, and means for normally closing the clutch; of means for opening the clutch, and means for serving the twofold purpose of shifting the gear and holding the clutch open until after 10 the gear is fully shifted.

6. The combination with the clutch and the shifting gear of a transmission-gear, and means for normally closing the clutch; of a lever for opening the clutch; said lever being 15 provided with a projection, a slide provided with means for engaging the projection and moving the lever in one direction, and a slide connected with and arranged to move the shifting gear and having one or more recesses 20 arranged to register with the projection of the lever to permit movement of the lever in the direction opposite to that stated; the second-mentioned slide being also arranged to derive motion from the first-mentioned 25 slide.

7. The combination with the clutch and the shifting gear of a transmission-gear, and means for normally closing the clutch; of a lever provided with a projection and connected with and adapted to open the clutch, a slide having one or more notches arranged 30 to engage the projection and swing the lever in one direction, and a slide connected with and arranged to move the shifting gear and having one or more recesses arranged to register with the projection of the lever to permit 35 movement of the lever in the direction opposite to that stated; the second-mentioned slide being loosely connected with the first-mentioned slide, whereby the second-mentioned slide will be moved by the first-mentioned slide subsequent to the initial movement of the latter.

8. The combination with the clutch and the shifting gear of a transmission-gear, and means for normally closing the clutch; of a lever for opening the clutch; said lever being 45 provided with projections, a cam-lever arranged to engage one projection and thereby 50 move the lever in one direction, and a slide connected with and arranged to move the shifting gear and having one or more recesses arranged to register with the other projection of the lever to permit movement of the 55 lever in the direction opposite to that stated.

9. The combination with the clutch and the shifting gear of a transmission-gear, and

means for normally closing the clutch; of a lever for opening the clutch; said lever being provided with projections, a cam-lever arranged to engage one projection and thereby move the lever in one direction, a slide having one or more notches arranged to engage the other projection of the lever to swing the lever in the same direction, and a slide connected with and arranged to move the shifting gear and having one or more recesses arranged to register with the last-mentioned projection of the lever to permit movement of the lever in the direction opposite to that stated; the second-mentioned slide being loosely connected with the first-mentioned slide, whereby the second-mentioned slide will be moved by the first-mentioned slide subsequent to the initial movement of the latter.

10. The combination with the clutch and the shifting gear of a transmission-gear, and means for normally closing the clutch; of a lever for opening the clutch; said lever being 80 provided with a projection, means for moving the said lever in one direction, and a device movable to and fro and connected with and arranged to move the shifting gear and having one or more recesses arranged to register 85 with the projection of the lever to permit movement of the lever in the direction opposite to that stated.

11. The combination with the clutch and the shifting gear of the transmission-gear, 90 and means for normally closing the clutch; of a lever provided with a projection and connected with and adapted to open the clutch, a device movable to and fro and having one or more notches arranged to engage 95 the projection and swing the lever in one direction, and a device movable to and fro and connected with and arranged to move the shifting gear and having one or more recesses arranged to register with the projection of 100 the lever to permit movement of the lever in the direction opposite to that stated; the second-mentioned device being loosely connected with the first-mentioned device whereby the second-mentioned device will be 105 moved by the first-mentioned device subsequent to the initial movement of the latter.

In testimony whereof I have hereunto set my hand in presence of two subscribing witnesses.

TERRY STAFFORD.
